UNITED STATES PATENT OFFICE.

VIRGIL W. MORAY, OF NEW YORK, N. Y.

ENGINE.

Application filed October 16, 1922. Serial No. 594,747.

To all whom it may concern:

Be it known that I, VIRGIL W. MORAY, a citizen of the United States, and a resident of the city of New York, county of the Bronx, and State of New York, have invented certain new and useful Improvements in Engines, of which the following is a full, clear, and exact description.

Among the principal objects which the present invention has in view are: to increase the power output of the engine without correspondingly increasing the number of moving parts connected therewith; to utilize the full expansive force of the power medium employed; to radiate the heat absorbed by the metal of which the engine is constructed; to efficiently lubricate the moving parts of the engine; and to simplify and cheapen the construction of the engine.

20

Drawings.

Figures 1 and 2 are horizontal longitudinal sections of an engine constructed and arranged in accordance with the present invention, the section being taken as on the line 1—1 in Figure 3 and Figure 1 showing one end portion of the engine and Figure 2 being a continuation of Figure 1, and showing the other end portion of the engine.

30 Figure 3 is a cross section of the engine, the section being taken as on the line 3—3 in Fig. 1.

Figure 4 is a longitudinal section taken through one of the pistons, and a fragment of the supporting shaft and cylinder therefor, the section being taken as on the line 4—4 in Figures 1 and 3.

40 Figure 5 is a longitudinal section taken through one of the pistons, and a fragment of the supporting shaft and cylinder therefor, the section being taken as on the line 5—5 in Figure 1 and in Figure 3.

45 Figures 6 and 7 are longitudinal sections of the pistons and parts connected therewith, shown in Figures 4 and 5, the sections being taken as on the line 6—7 and 6—7 in Figure 3.

50 Figures 8 is a cross section of the engine and one of the pistons therefor, the section being taken as on the line 8—8 in Fig. 4, showing the oil circulation and a part of the water circulation used in the present invention.

Figure 9 is a cross section of similar char-

acter, the section being taken as on the line 9—9 in Fig. 6.

Description.

Engines built in conformity with the present invention employ two series of moving pistons and supporting shafts therefor cooperatively connected with a rotary or driving shaft of an engine. Both series are mounted in a single continuous cylinder wherein they are reciprocated in relatively opposite directions and wherein the pistons form both the resisting and yielding power operated members. The medium constituting the motive power with which the engine is applied is introduced to the cylinder in coordination to the moving pistons to be delivered therebetween to secure the expansion or recession of each from the other when said medium is expanded.

Referring to the drawings, it will be seen that the cylinder 15 is tubular and elongated. At opposite ends thereof are fitted gas-tight heads 16. The heads 16 are bolted in place, suitable gaskets being used, and provide bearings through which the semi-circular shafts 17 and 18 pass. Glands 19 at opposite ends of the cylinder serve to wipe the piston rod. The packing at this point is loose enough to provide passage for air to prevent the same being trapped or compressed in the ends of the cylinder.

Several forms of power medium such as steam, explosive gases, or other medium, and expanded vapors may be employed. In the drawings I have illustrated the adaptation of the engine to the use of explosive gases. To radiate the heat developed in the cylinder 15, I provide the same with a series of annular fins 20. The fins 20 are subjected to air currents driven through the casing jacket 21 by means of a circulating fan 22.

As seen best in Figures 4 to 7 inclusive and in Figures 8 and 9, the piston rods 17 and 18 are semi-circular and formed as counter-parts each to the other. As shown best in Figures 4 and 5 of the drawings, the pistons A and B are bolted by means of flanges 23 to the piston rods 17 and 18 and are disposed in sliding relation to the piston rods 18 and 17 respectively, an oil groove 24 being formed in the said piston adjacent the shaft 18 for eliminating friction otherwise produced at this point. Wipers

25 are mounted at opposite sides of the groove for the purpose of preventing the too rapid emission of oil from the groove 24 and to utilize the oil as a packing member 5 for the pistons. Oil is delivered to the grooves 24 in the various pistons and returned to the oil channels as will be herein-after explained. The pistons are box-like having hollow centers which are supplied 10 with water for radiation from the channels 30 in the piston rods 17 and 18 as will be hereinafter brought out.

By reference to Figures 3, 8 and 9, it will be seen that the semi-circular shafts are 15 bored longitudinally to provide therein the channels 28 and 30. The channels 30 are connected at one end of the engine with a water supply by means of the pipes 31 as seen best in Fig. 4 of the drawings, while 20 the channels 28 are connected in a similar manner with an oil supply by means of pipes 32.

The pipes 31 and 32 are stationary and are 25 provided with pumping extensions 33 and 34 respectively. The extensions 33 and 34 are similarly provided with gravity valves 35, said valves opening into the channels 30 and 28 respectively. Packings 36 prevent the exudation of the oil and water around the 30 said extensions 33 and 34. The piston rods 17 and 18 slide freely and smoothly over the stationary extensions 33 and 34 and at each impulse towards the said extension, the piston rod and the contents of the channel 35 28 and 30 operate to close the valves 35 with the resultant displacement of the oil and water contained in the said channels, the said oil and water being moved in the 30 said channels in a relatively forward direction. It is obvious that after having made their strokes toward the extensions 33 and 34 the shafts move retractively with the result that the valves 35 are opened to deliver into the 45 said shafts the equivalent of the water or oil displaced therefrom by the previous forward movement of the said piston rods.

It will be understood that the valves 35 at the opposite ends of the machine open in the 50 same direction with the result that the said valves open to permit the water and oil at one end of the machine to enter the channels 30 and 28 while at the other end of the machine the valves open to admit the water and oil to the pipes 33 and 32. The operating 55 result of this is that the water and oil is forced into channels 30 and 28 at one end of the machine and drawn from the said channels at the other end of the machine thereby establishing a forced circulation of 60 water and oil through the said channels and pistons associated therewith.

As the water is displaced from the channels 30 it is carried by the passages 37 into the body of the pistons A where it is delivered 65 as close as convenient to the center of the

said piston. A return pipe 38 with an open receiving and adjacent the periphery of the piston A conveys the water from the first cylinder to the branch of the channel 30 connecting with the second cylinder of the same 70 series. A partition 39 interrupts the channel 30 to secure the circulation described.

An action similar to that described with reference to the water through the channels 30 and the piston A is produced in the oil circulating system with which the invention is provided by means of the delivery pipe 40 which is connected with the channel 28 on one side of the central partition and the return pipe 41 which takes the oil from the groove dash 24, at the diametrically opposite side of the piston to return it to the channel 28. This construction can be best seen in Figures 6 and 7 of the drawings.

From the foregoing it will be seen that if the two shafts 17 and 18 are reciprocated in relatively opposite directions as in the operation of the present machine they are, the water and oil supplied by means of the pipes 31 and 32 is circulated, the water and oil passing through the channels 30 and 28 and into the pistons A successively to the opposite ends of the said shafts where the said water and oil are returned to the source from which they were taken, there to be cooled or otherwise handled in a manner common to the radiating and oiling systems of internal combustion engines. This movement of the shafts is secured by expanding or exploding the expandible medium between pistons A and B and alternately at opposite sides thereof with the exception of the end pistons, the explosive operating these 90 happening on one side only.

When employing explosive fuel as produce by gasoline or other explosive gases, a series of manifolds 42 are employed, each operatively connected with a carburetor 43 of approved type. The manifolds 42 have access to the cylinder 15 through inlets closed by valves 44 of usual construction. The valve chambers 45 in which the said valves are mounted open to the interior of the cylinder 15. These chambers are preferably disposed at opposite sides of the said cylinder to the exhaust valve chambers 46 wherein the exhaust valves 47 are disposed. The chambers 46 open to the exhaust manifold 48 in the same manner as usually employed in internal combustion engines.

An ignition system of any approved type is employed wherein spark plugs 49 are used. The plugs 49 are connected with any suitable distributing system whereby ignition sparks are produced in the plugs 49 to ignite the combustible fuel in the cylinder 15 in timed relation to the operation of the shafts 17 and 18 and the pistons A and B thereon.

As shown in Figures 1 and 2, there are

five pistons, three pistons A, and two pistons B.

As above stated the pistons A are all mounted rigidly on the piston rod 17 while the pistons B are all mounted rigidly on the piston rod 18. When the pistons are disposed as shown in the said Figures 1 and 2, it is obvious that between the closely disposed pairs of pistons A and B there is between the one pair a compressed explosive fuel ready for ignition, and between the other, a space cleared of the dead gases consequent to the previous disclosure, while between the pairs of pistons A and B widely separated there must be in the one space a charge of explosive fuel ready to be compressed, and in the other space a fully expanded inert or combusted gases ready for evacuation through the exhaust mani-

fold 48.

With reference to the disposition of the shafts 17 and 18 and pistons A and B as shown in Figures 1 and 2 of the drawings, it may be conceived that counting from the left-hand of the combined figures the space indicated by the letter X contains compressed explosive fuel, while the space indicated by the letter Y has delivered its dead gases, the space indicated by the letter Z may be conceived to have a charge of explosive fuel ready to be compressed, while the space W contains fully expanded dead gases of the previous explosion. If now a spark is emitted from the plug 49 opposite the space X, the pistons A and B at opposite sides of the space X will be equally moved outward from the center of the space X by the explosion occurring therein. The shafts 17 and 18 will be moved correspondingly with the result that the explosive fuel in the space Z will be compressed ready for explosion. The space Y will be increased to draw in a charge of explosive fuel through the valve chamber 45 and manifold 42, while the dead gases in the space W will be driven off through the exhaust valve chamber 46 and the manifold 48. The explosive condition will then be found to have been set up in the space Z, the firing wherein then compresses the charge in the space Y and exhausts the dead gases from the space X, charging in turn the space W which charge will be compressed by the explosion which immediately transpires in the space Y and so on repeating the four cycles of the engine.

The shafts 17 and 18 are rigidly connected to cross heads 50 and 51, respectively, at one end of the said shafts. The cross heads 50 and 51 are operatively connected by the connecting rods 52 and 53 with the cranks 54 and 55 respectively. The cranks 54 and 55 are formed on the crank

shaft 56 which supports a flywheel 57.

As may be seen by reference to the drawings, the cranks 54 and 55 are oppositely disposed or set so that when the shafts 17 and 18 are reciprocated in opposite directions the propulsive impulse is imparted to the cranks in correspondence therewith. In this manner it is obvious that the rotary impulse imparted to the shaft 56 is balanced impulse, thereby eliminating all vibration therefrom.

The fan 22 is operatively connected with the shaft 56 by means of a transmission shaft 58, pulley 59 mounted thereon, and a belt 60 which is used to connect the pulley 59 and a pulley 61 on the fan shaft which is held in the bracket 62.

Claims.

1. An engine comprising a cylinder; a crank shaft having oppositely extended cranks; a plurality of pistons reciprocally mounted in said cylinder in paired relation; a plurality of piston rods each operatively connected with one of said cranks and with one of said pistons for movement thereby in relatively opposite directions; the piston rods being positioned in close side by side relation and extending axially of the cylinder and through said piston, and means for introducing an expansible medium between said pistons for moving the same in relatively opposite directions, simultaneously.

2. An engine comprising a cylinder; a crank shaft having oppositely extended cranks; a plurality of pistons reciprocally mounted in said cylinder in paired relation; a plurality of hollow concentrically arranged piston rods each operatively connected with one of said cranks and with one of said pistons for movement thereby in relatively opposite directions; said piston rods extending axially of the cylinder through the pistons, and means for introducing a power producing medium between said pistons for moving the same in opposite directions simultaneously.

3. An engine comprising a cylinder; a crank shaft having oppositely extended cranks; a plurality of pistons reciprocally mounted in said cylinder in paired relation; a plurality of relatively slidable piston rods, semi-circular in cross section with their flat faces abutting, extending axially of the cylinder through said pistons and each operatively connected with one of said cranks and one of said pistons, and means for introducing and exhausting a power producing medium between said pistons for effecting movement thereof simultaneously in opposite directions.

VIRGIL W. MORAY.
